UNITED STATES PATENT OFFICE.

JASPER F. BULLARD, OF LOACHAPOKA, ALABAMA, ASSIGNOR TO J. B. MCRITCHIE, OF LOACHAPOKA, ALABAMA.

PUMP.

1,117,942.

Specification of Letters Patent.

Patented Nov. 17, 1914.

Application filed July 15, 1912. Serial No. 709,528.

To all whom it may concern:

Be it known that I, JASPER F. BULLARD, a citizen of the United States, residing at Loachapoka, in the county of Lee, State of Alabama, have invented certain new and useful Improvements in Pumps; and I do hereby declare the following to be a full, clear, and exact description of the invention, such as will enable others skilled in the art to which it appertains to make and use the same.

This invention relates to improvements in pumps, and more particularly to a pump having double cylinders.

15 The invention has for its object to so construct a pump of this type that the same may be easily operated and will pump a continuous stream of water.

20 A further object of the invention is to so construct a pump of this kind that the same may be moved from place to place and may be positioned in proper respect to a source of water for pumping the same.

25 With these and other objects in view, this invention resides in the novel features of construction, formations, combinations and arrangements of parts to be hereinafter more fully described, claimed and illustrated in the accompanying drawing, in

30 which:—

Figure 1 is a side elevation of the pump. Fig. 2 is a rear elevation of the same. Fig. 3 is a vertical sectional view through the pump. Fig. 4 is a similar view taken at 35 right angle to Fig. 3. Fig. 5 is a sectional view on line 5—5 of Fig. 1. Fig. 6 is a fragmentary side elevation of one of the eccentrics. Fig. 7 is a sectional view on line 7—7 of Fig. 2. Fig. 8 is a perspective view 40 of one of the supports.

Referring to the drawing, the numerals 1 and 2 designate supports, each of which consists of legs 3 which are connected intermediate their ends by a bar 4, said bar being provided with perforations 5 and through which securing devices are passed to engage the double bored cylinder 6. The upper ends of the legs 3 are connected by bars 7, said bars being provided with bearings 8 in which are journaled the opposite ends of the shaft 9, said shaft having a crank handle 10 formed at one end, adjacent which is fixed a fly wheel 12. Fixed to the shaft 9 and arranged in spaced rela-

tion are eccentrics 13, the peripheries of 55 which are provided with grooves 14 in which is supported the bands 15, said bands being provided with extensions 16, the purpose of which will appear later.

From the construction thus far it will be 60 seen that the cylinder 6 will be supported above the ground a sufficient distance so that the entire device may be moved from place to place without interference with the cylinder in any way. The cylinder 6 is pro- 65 vided with a pair of bores 17 and in which reciprocate pistons 18 having connected therewith piston rods 19 the upper ends of which are bifurcated and between the fur- 70 cations 20 thereof is secured pivotally the 70 lower ends of the links 21, the upper ends of which are similarly connected to the ex- 75 tensions 16, whereby when the crank 10 is grasped and operated the shaft 9 will turn and impart reciprocatory movement to the 75 pistons 18.

Having communication with the lower end of the bores 17 of the cylinder are nipples 22 having connected thereto trans- 80 versely arranged pipe sections 23 which are 80 in turn connected to the pipe sections 24 which are arranged in parallel relation and have their ends provided with angularly disposed sections 25 which are in turn con- 85 nected to an inlet pipe 26, said pipe being 85 provided with valves 27, which operate to permit water to be drawn into the bores of the cylinder upon the up stroke of the pis- 90 ton and will prevent water from being forced backward in the pipe sections upon 90 the down stroke of the pistons, the water acted upon by the down stroke of the piston being forced outwardly through the pipe sections 28, which have communication 95 through the cylinder with the bores 17 at a point above the upper ends of the nipples 22, said sections 28 being connected to pair of parallel arranged pipe sections 29, the outer ends of which are provided with angularly disposed pipe sections 30 the meet- 100 ing ends of which are provided with an outlet pipe 31, through which the water is forced to its point of use. The pipe sec- 105 tions communicating with the outlet pipe 31 are provided with a check valve, the same being designated by the numerals 33, and operate to permit the water to be forced outwardly through the sections, and will

prevent water from entering the bores 17 of the cylinder upon the upstroke of the piston.

What is claimed is:—

5 A force pump comprising a cylindrical member having two longitudinally extending parallel bores open at their upper ends and apertures in their lower ends, pipes communicating with said apertures and connected to a common exhaust pipe, a bifurcated supply pipe communicating with said bores above the apertures in their lower ends, supports for said cylindrical members comprising inverted U-shaped members secured to said cylindrical members at their 10 bight portions, upwardly extending inverted

U-shaped members secured to the bight portions of the first named members, bearings mounted on the upper ends of the last mentioned U-shaped members, oppositely actuated eccentrics upon said shaft, straps loosely surrounding said eccentrics, pistons connected to said straps and arranged to be alternately actuated by said eccentrics, and actuating means for the eccentrics. 20 25

In testimony whereof, I affix my signature, in presence of two witnesses.

JASPER F. BULLARD.
